(57) **CLAIM**

The ornamental design for a wakeboard tower, as shown and described.

DESCRIPTION

FIG. 1 is a perspective illustration, from the front and right side, of the wakeboard tower of my design;

FIG. 2 is a top view thereof;

FIG. 3 is a right side view thereof, the left side view being a mirror image of illustrated right side view;

FIG. 4 is a front view thereof; and,

FIG. 5 is a rear view thereof.

The broken line showing of environmental structure in FIG. 1 is for illustrative purposes only and forms no part of the claimed design.
